UNITED STATES PATENT OFFICE.

OTTO A. BANNER, OF MILWAUKEE, WISCONSIN, ASSIGNOR TO THE FALK CORPORATION, OF MILWAUKEE, WISCONSIN, A CORPORATION OF WISCONSIN.

OIL ENGINE.

Application filed March 17, 1922. Serial No. 544,414.

This invention relates to oil engines, and more particularly, to that type of engines in which a restricted passage or throat is employed between the compression chamber 5 and the working portion of the cylinder.

One object of the present invention is to improve the combustion in engines of this type.

Other objects and advantages will hereinafter appear.

Embodiments of this invention are illustrated in the accompanying drawings, in which:

Figure 1 is a fragmentary sectional view 15 of the cylinder of an oil engine constructed in accordance with the present invention.

Figure 2 is a sectional view taken substantially on the line 2—2 of Figure 1.

Figure 3 is a view similar to Figure 1 20 illustrating the cylinder of an oil engine of somewhat different form.

The engines selected for illustration are oil engines of the four cycle upright type, although the invention is equally applicable 25 to two cycle engines and to engines of the horizontal type. The engine shown in Figures 1 and 2 includes one or more cylinders 10 of any standard or approved construction water jacketed in the usual manner and enclosing a piston 11 of usual form. The cylinder head 12 is provided with the usual exhaust and air intake valves 13 and 14. A water cooled partition 15 is arranged beneath the cylinder head 12 in such position 30 as to form a chamber 16 segregated from the working portion of the cylinder and communicating therewith through a restricted throat or passage 17. The chamber 16 extends transversely of the cylinder and is 35 of substantially flat, elongated form, of such dimensions as to readily accommodate the valves 13 and 14. The partition 15 is preferably formed as a part of a member 18 removably interposed between the cylinder 40 head and cylinder so as to permit ready access to the chamber 16.

In this instance, the passage 17 is arranged adjacent one end of the chamber 16 so that the air forced through the passage 50 17 during the compression stroke will travel toward the other end of the chamber. The fuel is injected into the chamber, preferably in a direction contra to the direction of the flow of air therein and preferably imme-

diate prior to compression dead center. In 55 this instance, a single injection nozzle 19 of the solid injection or pump spray type is employed. The nozzle shown is of the type described in the copending application of Otto A. Banner and Jacob Schlumberger, 60 filed March 17, 1922, Serial No. 544,427. It will be sufficient here to say that this nozzle includes a pair of convergent fuel discharge ducts by which two jets of fuel spray are produced, which meet at a point and 65 spread out to form a substantially flat fuel spray which substantially fills the chamber. The impact of the fuel jets reduces the velocity of the fuel particles so that they are not thrown directly against the chamber 70 walls.

An engine constructed and operated in the manner above described has been found to give excellent results when operated at rather 75 high compression pressures, though it is not necessary to employ compression pressures as high as those commonly required in the Diesel engine, in which the fuel is injected by means of highly compressed air. Furthermore, though a prompt and complete combustion occurs, it does not occur as a violent explosion, as in the case of other engines operating on the Otto cycle.

It will be noted that in the engine shown 85 in Figure 1 the upper wall of the partition 15 is substantially parallel to the upper wall of the chamber 16 so that the chamber is of substantially uniform depth from end to end. The shape of this chamber, however, might be varied somewhat from that shown. 90 For instance, as shown in Figure 3, the upper wall of the partition 15 might be inclined downwardly toward the passage 17 to accommodate a downwardly inclined spray.

Various other changes may be made in the embodiments of the invention hereinabove described, without departing from or sacrificing any of the advantages of the invention as defined in the appended claims.

I claim:

1. In an internal combustion engine the combination of a cylinder having an elongated chamber extending transversely thereof, intake and exhaust valves in one wall of said chamber, a restricted passage through the opposite wall of said chamber at one end thereof, means for cooling the walls of said

chamber, and means at the other end of said chamber for directing a fuel spray extending longitudinally thereof.

2. In an internal combustion engine the combination of a cylinder having a cylinder head, a water cooled partition in said cylinder cooperating with said head to form an elongated chamber, an opening through said partition at one end of said chamber, and an injection nozzle at the other end of said chamber for directing a fuel spray longitudinally thereof.

3. In an oil engine the combination of a cylinder having an elongated chamber extending transversely thereof, said chamber being rectangular in transverse section, means for cooling the walls of said chamber, a passage adjacent one end of said chamber effecting communication with said chamber

and cylinder, and an injection nozzle at the other end of said chamber for producing a substantially flat fuel spray directed longitudinally thereof.

4. In an oil engine the combination of a cylinder having a shallow elongated chamber extending transversely thereof, said chamber having a substantially flat wall, intake and exhaust valves in said wall, the opposite wall of said chamber having a passage therethrough adjacent one end thereof, means for cooling the walls of said chamber, and an airless fuel injection nozzle at the other end of said chamber for producing a substantially flat fuel spray directed longitudinally thereof.

In witness whereof, I hereunto subscribe my name this 2nd day of March, 1922.

OTTO A. BANNER.
